UNITED STATES PATENT OFFICE.

ANDREW F. HENNINGER, JR., OF CHICAGO, ILLINOIS, ASSIGNOR, BY DIRECT AND MESNE ASSIGNMENTS, TO THOMAS H. BRENNAN, OF CHICAGO, ILLINOIS.

CONSTRUCTION FOR INDUCTANCES.

Application filed August 11, 1924. Serial No. 731,361.

To all whom it may concern:

Be it known that I, ANDREW F. HENNINGER, Jr., a citizen of the United States, and a resident of the city of Chicago, county of Cook, and State of Illinois, have invented certain new and useful Improvements in a Construction for Inductances, of which the following is a specification.

My invention relates to a construction for inductances, and has for its principal object the provision of an improved structure of this character which will be highly efficient in use and economical in manufacture.

One of the main objects of my invention is the provision of an improved construction of the character described, in which the coils are so mounted and related as to reduce or to tend to reduce, to a minimum the losses of electrical energy due to dielectric absorption, to dielectric leakage and to inter-turn losses.

A further object of my invention is the provision of a construction of this character which is designed especially to diminish the losses of electrical energy and as well to diminish or eliminate the undesirable effects which result from such losses, when inductances are employed instruments for radio sets in the form of tuning inductances, tuned radio frequency transformers, vario-couplers, variometers and the like.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side elevational view of a construction made in accordance with my improvements;

Fig. 2 is an end elevation thereof; and

Fig. 3 is a cross sectional view, taken substantially on the line 3—3 of Fig. 2.

By those familiar with the art of wireless telephony and wireless telegraphy, it will be readily understood that loss of electrical energy with the disturbing results which flow therefrom, is in most instances due principally to winding the inductances upon an inefficient dielectric. In all dielectrics, there is a certain amount of energy depletion, va-

rying with the amount of material and the method of its construction. In radio sets, dielectric loss of energy is frequently attended by most undesirable results. For example, in a radio receiving set, employing radio frequency amplification and a tuned inductance for each stage of radio frequency amplification, energy losses in the tuning inductances and in each tuned radio frequency transformer decrease appreciably the range of reception and affect volume and selectivity. The sensitivity of a vacuum tube detector is proportional to the square of the voltage applied to it. If, therefore, half of the incoming energy is lost in the tuning inductances, the signal strength in the plate circuit of the detector tube will be but one-fourth of what it should be. Again, in view of the powers of amplification of the audio amplifier, it will be apparent that a slight decrease in the energy as applied to the grid of the detector tube, will cause a heavy decrease of volume in the output of the two stage audio frequency amplifier.

In referring with particularity to the embodiment of my invention illustrated in the accompanying drawing, it will be seen that the construction includes two end rings 4 and 4' which are connected at equi-spaced intervals by pairs of strips 5 and 5', of which 5 represent inner strips being secured to the rings on the inner periphery thereof while 5' represent outer strips being secured to the rings on the outer periphery thereof. The rings and the strips are all made of insulation material, preferably of bakelite. Through each pair of outer and inner strips and the intervening rings are passed bolts 6 having threaded portions for the reception of securing nuts 7, whereby these parts are detachably secured together. In this manner I provide a simple, light skeleton frame of cylindrical form, and one in which the solid dielectric is reduced approximately to a minimum.

Each of the inner strips 5 is provided on its inner face with a recess 8 of a depth suitable for the reception of a primary coil 9. The said recesses 8 extend longitudinally of the strips for a distance sufficient to accommodate the extent or spread of the coil to be placed therein. For securing the coil 9 in the recesses of the strips, I secure to each

strip an insulating bridging member 10, the method of securement consisting preferably in the use of celluloid cement.

Before the outer strips 5' are secured in place I wind upon the inner strips 5 another or secondary coil 11. Obviously, the number of turns of the coil 11 will govern the amount or increase of voltage to be induced therein. According to an important feature of my improvements, I provide means for causing the outer strips 5' to have uniform pressure or engagement upon the several turns of the coil 11. From an inspection of Fig. 3, it will be seen that the outer strips 5' at their extremities are provided with recesses 12, adapted to receive the end rings. The horizontal walls defining these recesses are not made parallel with the end rings, but the same are fashioned at an angle thereto in the form of an outward inclination so that the regions indicated at 13 will be of less thickness than the regions indicated at 13'. In consequence of these formations, the outer strips 5' when they are drawn down tightly on the end rings by the screw connections 6, have a tendency to be flexed between the end rings towards the inner strips 5, so that the turns of the inter-engaged coil will be held uniformly in the positions at which they are wound upon the inner strips 5. The opposite ends of the coil 9 are extended to the points 14 and 15 where they are soldered to the screws as 6 in order to provide terminals. The opposite ends of the other coil 11 are extended to other convenient bolts as 6 to provide terminals 16 and 17. With the bolts 6 are secured lugs or anchor plates 18 to which parts to be supported on or in connection with the structure may be attached or soldered as desired. The structure is supported upon brackets 19 formed with feet 19' which may be secured upon a base board as 20, or upon any suitable support of the radio instrument in which the structure is to be incorporated.

From the foregoing description, taken in connection with the accompanying drawing, it will be seen that I have provided a very simple construction, in which air is employed as the dielectric with only relatively slight points of solid dielectric support for the coils, so that through a lessening of the losses of electrical energy, there will be a substantial improvement in the operation of the radio sets, and further so that there will be less interference from distant stations by nearer and more powerful stations transmitting on a different wave length.

While I have illustrated and described the preferred form of construction for carrying my invention into effect, this is capable of variation and modification without departing from the spirit of the invention. I, therefore, do not wish to be limited to the

precise details of construction set forth, but desire to avail myself of such variations and modifications as come within the scope of the appended claims.

Having described my invention, what I claim as new and desire to secure by Letters Patent is:

1. A coil support comprising a plurality of relatively thin and narrow bars of dielectric material on which the coil is mounted, a pair of rings of dielectric material of substantially the same diameter as the coil, said rings being mounted on said bars adjacent each end of the coil, a plurality of bars of dielectric material positioned on said coil opposite said first mentioned bars, notches formed adjacent the ends of said last mentioned bars, said notches having an angular wall engaging said rings, and bolts extending through said bars and rings whereby the coil is compressed between the bars and the latter are held in true circular formation, substantially as described.

2. A coil support comprising a plurality of relatively thin and narrow bars of dielectric material on which the coil is mounted, a pair of rings of dielectric material of substantially the same diameter as the coil, said rings being mounted on said bars adjacent to each end of the coil, a plurality of bars of dielectric material positioned on said coil opposite said first mentioned bars, notches formed on the inner faces of the end portions of said last mentioned bars, said notches accommodating the end rings and being of sufficient depth to permit the opposing faces of the first and second mentioned bars to firmly clamp the convolutions of the coil between them notwithstanding the increased thickness of the rings as compared to the wire of the coil, and means for firmly clamping the first and second mentioned bars towards each other, substantially as described.

3. A coil support comprising a plurality of relatively thin and narrow bars of dielectric material on which the coil is mounted, a ring of dielectric material of substantially the same diameter as the coil, said ring being mounted on said bars adjacent to one end of the coil, a plurality of bars of dielectric material positioned on said coil opposite to said first mentioned bars, one set of bars being recessed to receive the ring to permit approach of the opposing faces of the bars towards each other sufficiently close to ensure direct clamping action of said faces on the convolutions of the coil notwithstanding the increased thickness of the ring as compared to the wires of the coil, substantially as described.

In testimony whereof I have signed my name to this specification.

ANDREW F. HENNINGER, JR.
